No. 14,824

FEB 26, 1884

UNITED STATES PATENT OFFICE.

CATHERINE SHIELS, OF NEW YORK, N. Y., ASSIGNOR TO THE BUTTERICK PUBLISHING COMPANY, (LIMITED,) OF SAME PLACE.

DESIGN FOR A CHILD'S COSTUME.

SPECIFICATION forming part of Design No. 14,824, dated February 26, 1884.

Application filed January 23, 1884. Term of patent 3½ years.

To all whom it may concern:

Be it known that I, CATHERINE SHIELS, of the city, county, and State of New York, have invented and produced a new and original Design for a Pattern of a Child's Costume, numbered 9,032; and I do hereby declare that the engraved prints accompanying this specification convey to any one accustomed to using paper patterns a clear understanding of how a garment made up by the pattern will appear.

The design shows a half-fitted body-back, widened and lengthened to form the back of the skirt, and exhibiting under-folded plaits at the lower end of its center seam, and at a corresponding point at its front edges; short under-fronts displaying buttons all the way down and exposed between the reversed edges

of jacket-fronts that display side skirts flaring widely at their front edges and falling over a side-plaited portion representing the skirt for the front and sides; a deep shoulder-cape flaring widely at its front edges; a standing collar, and coat sleeves displaying pointed demi-cuff facings on their upper sides.

What I claim as my invention, and desire to secure by Letters Patent, is—

The design for a child's costume, as shown in the engraved prints accompanying this specification.

CATHERINE SHIELS.
